FIRE EXTINGUISHING COMPOSITION

Albert Langlois, Fall River, Mass.

No Drawing. Application February 2, 1934,
Serial No. 709,534

6 Claims. (Cl. 23—8)

This invention relates to fire extinguishing compositions and it comprises a powdered mixture of sodium bicarbonate, potassium bitartrate, boric acid and borax to which I advantageously add pulverized rice and ultra-marine blue, the resulting mixture being one which is adapted to be cast upon a fire such as, for example, burning gasoline or oil.

There are a number of fire extinguishing compounds in solid powdered form available, but these generally suffer from a number of disadvantages. In the first place, their action is not always immediate because they generally consist of a gas evolving material such as bicarbonate or carbonate which does not decompose at very low temperatures. Therefore, some little time often elapses before the fire extinguishing compound begins to evolve carbon dioxide. Practically all of the present types of compositions for this purpose contain sodium carbonate or bicarbonate. In the case of the bicarbonate, carbon dioxide is liberated fairly rapidly, but not immediately; sodium carbonate gives up its carbon dioxide content less readily. Very few of the present-day solid fire extinguishing compounds are at all suitable for extinguishing oil and gasoline fires. Present-day practice in connection with this problem generally requires the use of an extinguishing compound in a liquid state, such for example as "fire foam" and other compositions which develop a blanket of heavy foam upon the burning surface of the oil.

I have now discovered that it is possible to create an enveloping air-excluding foam-like layer upon burning oil or gasoline from solid extinguishing compositions. My invention makes use of the dual action of sodium bicarbonate and a tartrate whereby I am able to get an immediate evolution of carbon dioxide at temperatures much lower than the decomposition temperature of the sodium bicarbonate alone. At the same time I also provide in my composition an excess of sodium bicarbonate so that after the reaction between the bicarbonate and the tartrate has exhausted the available tartrate, a further evolution of carbon dioxide from the surplus sodium bicarbonate takes place.

This means that immediately upon throwing my fire extinguishing compound upon the flames, carbon dioxide is evolved by reaction between the bicarbonate and the tartrate. During the course of this preliminary evolution of carbon dioxide from this reaction, the sodium bicarbonate itself is being heated up to decomposition temperature

whereupon it decomposes with the liberation of great quantities of non-combustible gas.

I also provide in my composition fluxing agents, namely, borax. At the high temperature of the fire, the borax will act as a flux and combine with the solid decomposition product of the bicarbonate and the tartrate. The resulting molten mass is fluid and forms a film on the surface of the oil or gasoline. Since, at the same time, evolution of carbon dioxide is taking place from undecomposed sodium bicarbonate, the minute bubbles of gas become disseminated through the molten borax whereby a fine foam-like, though very thin, layer forms on the surface of the burning oil.

I also include in my composition a relatively large quantity of boric acid. This helps in preventing any spontaneous reaction between the sodium bicarbonate and the tartrate while the fire extinguishing compound is kept in packages prior to use. The acid also assists in the decomposition of the tartrate to tartaric acid at the time the composition is brought in contact with the flames. I also believe, although I have not been able to satisfy myself conclusively, that the boric acid displays considerable fluxing action as well. At least it melts at the temperature of the fire and tends to form a film-like coating over the burning surface, which coating becomes blown up or aerated with fine bubbles of carbon dioxide.

One mixture I have found very suitable for the purpose of the present invention is as follows:

	Parts by weight	35
Sodium bicarbonate	48	
Potassium bitartrate	4 1/2	
Boric acid	12	
Borax	1 1/2	

To this mixture I find it advantageous to add 6 parts by weight of pulverized rice and 1 part by weight of ultra-marine blue.

These proportions may vary within reasonable limits, but I prefer that the composition shall contain a major quantity of sodium bi-carbonate, that the potassium bitartrate shall be considerably less than the bicarbonate, and that the boric acid shall be less than the bicarbonate but considerably more than the bitartrate. A relatively small amount of borax is sufficient since not very much of it is required to give an adequate fluxing action.

As pointed out above, when the composition is thrown upon the flames, the bicarbonate reacts

with the tartrate according to the following reaction:

- 5 This reaction, as stated above, occurs at relatively low temperature so there is an immediate evolution of carbon dioxide. As the sodium bicarbonate is heated up, it too decomposes, eventually yielding carbon dioxide and sodium oxide. At the same time the boric acid is reacting with the sodium potassium tartrate to liberate free tartaric acid which in turn decomposes to carbon dioxide and water; and the boric acid also 10 combines with the sodium and potassium oxides to give borates. These borates melt and form a film or layer on the burning oil, which layer 15 contains very fine microscopic bubbles of carbon dioxide gas.
- 10 I find it advantageous to incorporate pulverized rice as noted above. This material appears to act as a hygroscopic agent to prevent the powdered composition from becoming lumpy due to absorption of moisture. Moreover, it also 15 functions to assist in the formation of the blanket of carbon dioxide and the foam formed therefrom. Ultra-marine blue, noted above, gives added weight or body to the powdered composition and makes it far more effective, especially 20 when used on gasoline fires.

As stated above, the proportions of ingredients can vary materially from those specifically recited. The sodium bicarbonate can vary from 25 to 60 parts, the tartrate from 3 to 10 parts, the boric acid from about 6 to 20 parts, and the borax from about 1 to 3 or 4 parts. However, 30 it is desirable to maintain at all times a greater

quantity of sodium bicarbonate, a somewhat lesser quantity of boric acid, and a still smaller amount of the potassium tartrate.

My composition is used in the ordinary manner of using powdered fire extinguishing compositions. The powder is simply thrown upon the flames, usually from a package or cylindrical metal container.

Having thus described my invention, what I claim is:

1. A fire extinguishing composition comprising a dry powdered mixture of sodium bicarbonate, potassium bitartrate, boric acid, and borax, the mixture being adapted for casting upon a fire in its dry powdered condition. 10

2. A fire extinguishing composition comprising a dry powdered mixture containing a major quantity of sodium bicarbonate, a somewhat lesser quantity of boric acid, a somewhat lesser quantity of potassium bitartrate, and a small amount 20 of borax, the mixture being adapted for casting upon a fire in its dry powdered condition.

3. A fire extinguishing composition comprising 48 parts by weight of sodium bicarbonate, 12 parts by weight of boric acid, 4½ parts by weight of 25 potassium bitartrate, and about 1½ parts by weight of borax.

4. A fire extinguishing composition as in claim 1, including pulverized rice and ultra-marine blue. 30

5. A fire extinguishing composition as in claim 2, including pulverized rice and ultra-marine blue.

6. A fire extinguishing composition as in claim 3, including pulverized rice and ultra-marine blue. 35

ALBERT LANGLOIS.
